Jones, Addington, Ames & Leibbold

ATTORNEYS

UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ATTACHMENT PLUG.

Application filed May 18, 1922. Serial No. 561,863.

To all whom it may concern:

Be it known that I, REUBEN B. BENJAMIN, a citizen of the United States, residing at Chicago, in the county of Cook and State of Illinois, have invented new and useful Improvements in Attachment Plugs, of which the following is a full, clear, concise, and exact description, reference being had to the accompanying drawing, forming a 10 part of this specification.

My invention relates to attachment plugs and more particularly to separable swivel attachment plugs having an extension handle.

15 One of the objects of my invention is to provide a separable attachment plug arranged to receive a standard attachment plug cap and provided with an extension handle for facilitating the insertion of the 20 plug in places which are difficult of access with the ordinary attachment plug.

Another object of my invention is to provide a separable swivel attachment plug which will be easy to assemble, durable and 25 efficient in use, and cheap to manufacture.

Further objects will appear from the detailed description to follow and from the appended claims.

In the drawings in which an embodiment 30 of my invention is shown:

Figure 1 is a vertical longitudinal section through my improved separable swivel attachment plug, a part of the handle being shown in full lines, and a standard cap being shown in dotted lines;

Fig. 2 is a side elevation of the separable swivel attachment plug shown in Fig. 1, a portion of the handle being broken away;

Fig. 3 is a top plan view of the plug as 40 shown in Fig. 2;

Fig. 4 is a transverse section taken on a line 4—4 of Fig. 1;

Fig. 5 is a transverse section taken on line 3—3 of Fig. 1; and

Fig. 6 is a plan view of the center contact insulating washer.

Referring now to the drawings in my invention as illustrated, I provide an insulating base 10, having openings 11 and 12 therein, arranged to receive blade engaging contacts 13 and 14 respectively. Openings 15 are provided in the base 10 to permit the insertion of the blades 16 of an attachment plug cap 16^a into the openings 11 and 12, 55 in order to electrically engage the contacts

13 and 14. A threaded shell contact 17 surrounds the base 10 and is rotatably mounted thereon by means of the inwardly extending flange 18, resting in the annular groove 19 on the top of the base.

A stamping 20 is supported on the upper end of the base 10 and arranged to engage the flange 18 of the threaded shell contact 17. In order to prevent relative movement of this stamping with relation to the base, 65 it is provided with the lugs 21, which are engaged in the notches 22 in the extending portion 23 of the base 10. The stamping 20 is also provided with an arm 24 extending into the opening 12 in the base, to which 70 arm is secured the blade engaging contact 14. The stamping 20 is securely clamped against the base by means of the center contact 25 and the insulating washer 26, the insulating washer 26 having an opening 27, 75 partially conforming to the contour of the projecting portion of the base, thereby preventing relative rotation of the parts. The parts are securely held in operative position by means of the eyelet 28, which is preferably molded in the base 10 as shown.

The center contact 25 is provided with an arm 29 extending through the opening 27 in washer 26 and into the slot 11 in the base, to which arm is secured the contact 85 member 13. The contact members 13 and 14 are arranged to engage the blades of a standard attachment plug cap when they are inserted in the openings 16 in the usual manner.

The threaded shell contact 17 is provided at its lower end with an outwardly extending flange 30, which is secured between the insulating washers 31 and 32 by means of the ring or casing 33. The ring or casing 95 33 is pressed tightly over the edges of the washers 31 and 32, thus securing rigidly together all of the various parts of the swivel shell portion of the plug. The flange 30 is provided with portions 34, arranged to 100 co-operate with openings 35 in the washers 31 and 32, to prevent relative movement of the parts.

The ring or casing 33 is provided with 105 downwardly extending ears 36 on which is pivoted at 37 the extension handle 38. The handle is held in longitudinal relation to the plug by means of the locking member 39, arranged to impositively engage in the opening 40. The resiliency of the ear 36 110

and the handle 38 allow the handle to be placed in any desired angular position relative to the plug.

The base 10 extends somewhat below the washer 32 in order to prevent friction against the attachment plug cap when it is desired to rotate the shell with the cap in place.

In operation the plug may be inserted, 10 by means of the extension handle, in deep shades or places where it would be difficult to screw in the usual standard attachment plugs, and the cap then be inserted, or the cap may be first inserted in the plug 15 and the plug may then be easily screwed into a receptacle in a deep shade without twisting the cord, as the handle swivels around the cord in screwing the plug into place. After the plug is in place the handle 20 may be moved to one side as far as the shade will permit, thus giving a freedom of movement to the cord and preventing an unnecessary side strain on the fixture or the socket.

25 While I have shown but one form of my invention it is obvious that it may be embodied in other forms as covered and defined by the appended claims.

What I claim as new and desire to secure by Letters Patent of the U. S. is:—

30 1. An attachment plug comprising, in combination, a base, a swivel shell contact surrounding said base and supported thereon, a center contact on said base, a blade engaging contact electrically connected with said center contact, a second blade engaging contact electrically connected with said swivel shell contact, said swivel shell contact having a flange thereon, a pair of insulating discs supported on said flange, a casing 35 clamping said discs on said flange, and an extension handle secured to said casing.

40 2. An attachment plug comprising, in combination, an insulating base, a swivel shell contact surrounding said base and sup-

ported thereon, a center contact on said base, a blade engaging contact electrically connected with said center contact, a second blade engaging contact electrically connected with said swivel shell contact, said swivel shell contact having a flange thereon, a pair of insulating discs supported on opposite sides of said flange, a casing 50 clamping said discs on said flange, a pivoted extension handle secured to said casing, and means on said casing cooperating with said handle to impositively hold said handle in longitudinal relation to said plug.

3. A separable swivel attachment plug comprising, in combination, an insulating 55 base, a swivel shell contact surrounding said base and rotatably supported thereon, a center contact on said base, a blade engaging contact electrically connected with said center contact, a second blade engaging contact electrically connected with said swivel shell contact, said swivel shell contact having a flange thereon; a pivoted extension handle supported on and insulated from said flange, and means supported on 60 said flange for impositively holding said handle in longitudinal relation with said plug.

4. A swivel shell attachment plug comprising an insulating base, a threaded shell 65 contact mounted on said base, an extension handle pivotally mounted on said threaded shell contact, and means for holding said extension handle in alinement with said plug.

5. A swivel attachment plug comprising an insulating base, a threaded shell contact swiveled with respect to said base, an extension handle pivotally mounted on said threaded shell contact, and means for im- 70 positively holding said handle in longitudinal relation with respect to said plug.

In witness whereof, I have hereunto subscribed my name.

REUBEN B. BENJAMIN.
